UNITED STATES PATENT OFFICE.

HOWARD H. HOFFMAN, OF FAIRFIELD BEACH, CONNECTICUT, ASSIGNOR TO THE LAKE TORPEDO BOAT COMPANY, OF BRIDGEPORT, CONNECTICUT, A CORPORATION OF MAINE.

HOUSED CLEAT FOR SUBMARINE BOATS.

1,402,496.

Specification of Letters Patent.

Patented Jan. 3, 1922.

Application filed May 3, 1921. Serial No. 466,551.

To all whom it may concern:

Be it known that I, HOWARD H. HOFFMAN, a citizen of the United States, residing at Fairfield Beach, in the county of Fairfield 5 and State of Connecticut, have invented a certain new and useful Improvement in Housed Cleats for Submarine Boats, of which the following is a full, clear, and exact description.

10 Upstanding fixed cleats on submarine boats not only present speed-resisting surfaces, but they are a source of danger in their liability to catch in nets laid to entrap such boats when submerged, unless the cleats are 15 provided with special guards to avoid such nets.

The object of this invention is to avoid both of these difficulties, and to this end the invention consists of a disappearing cleat 20 that may thus be wholly removed out of sight and from obstructive and endangering possibilities when the boat is submerging, as I will proceed now to explain and finally claim.

25 The invention, however, is applicable to other than submarine boats.

In the accompanying drawings illustrating the invention, in the several figures of which like parts are similarly designated, 30 Figure 1 is a plan view of a portion of the forward end of a deck, with the cleats in extended or operative position. Fig. 2 is a side elevation, on a larger scale, and also showing the cleat by dotted lines in dis- 35 appearing or concealed position. Fig. 3 is a cross-section, on line 3—3, Figs. 1 and 2. Fig. 4 is a cross-section showing the cleat in disappearing or concealed position. Fig. 5 is a longitudinal section on line 5—5, Figs. 1 40 and 6, some parts being broken away to expose others. Fig. 6 is a top plan view of a portion of one side of a boat, illustrating the cleat in operative position, one end of one of the arms of the cleat being broken 45 away to expose one of the cleat bearings.

1 designates the superstructure of a boat, 2 the deck, and 3 the sides, which may be of any usual or approved construction.

At points where cleats are desired, the boat 50 is provided with wells or pockets 4, within which the cleats may be caused to disappear when not in use, or, in other words, within which the cleats may be housed. These wells or pockets may be provided with draining

openings 5. Within each well next to the side are fixed bearings 6 to receive pivots 7 formed on or applied to the base or bottom 8 of the cleat 9, the upper portion of which has the usual arms as shown. 10 is a plate extending from base 8 substantially at right angles to the cleat and having the solid portion 11 to close the opening in the well automatically as the cleat is raised from the well into operative position and to lie approximately flush with the deck at such times. 12 is a bracket applied to the wall of the well opposite the bearings 6, and having a pair of eyes 13. The plate 10 has a perforated lug 14 adapted to fit in between the eyes 13 and to be engaged therewith by a coupling pin 15 or other removable fastening medium, to hold the cleat in its extended or operative position. The pin 15 may be provided with a chain 16 engaging a fixed eye 17 to prevent its loss. The top of the cleat 75 may be provided with a lug 18 which engages the pin 15 on its lower side when the cleat is housed, in order to prevent displacement of the cleat as a result of the rolling and plunging of the boat. 80

19 is a cover for the well, same being hingedly connected with the boat so as to be capable of being turned over backward on to the deck, when the cleat is exposed, as in Figs. 1 and 3, or to be closed down over 85 the well, when the cleat is housed, as shown in Fig. 4.

The operation would seem to be obvious from the foregoing, but it may be restated as follows: The cleats are housed in the wells 90 when not in use, as shown in Fig. 4, and the wells closed securely, so as to avoid pitfalls for those on board as well as to conceal and protect the cleats, and to deliver a submarine boat from danger of having its cleats enmeshed in destroyer nets. Whenever a cleat is to be used, the cover 19 is opened and the cleat turned over, and locked in extended position, as shown in Figs. 1, 2, 3, 5 and 6, but ready to be returned quickly to its well 95 at any time.

Variations in details of construction and arrangement are considered to be within the spirit and scope of the invention as herein claimed.

What I claim is:

1. A disappearing cleat for boats, comprising a cleat of otherwise substantially or-

dinary construction, provided with pivots, and means to pivotally mount the cleat in a well in a boat, said cleat having a well-closing portion operative to close the well when 5 the cleat is exposed.

2. A cleat and a housing therefor, the two provided with complemental means for pivoting the cleat in the housing and for supporting it in useful position outside of the 10 housing and concealing it within the housing, said cleat having a portion for closing the housing when the cleat is exposed, and a supplemental cover for closing the housing when the cleat is concealed.

15 3. A cleat and a housing therefor, means for pivotally mounting the cleat in the housing so that it may be turned out of the housing into operative position and concealed within the housing in inoperative position, 20 and means to positively detain the cleat in either position.

4. A cleat and a housing therefor, said housing having bearings and the cleat having pivots mounted in said bearings, a plate 25 extending from the base of the cleat substantially at right angles and adapted to close the opened housing when the cleat is in operative position, and means to lock the parts in such position.

30 5. A cleat and a housing therefor, complemental means in the housing and on the cleat for pivotally mounting the cleat within the

housing, means for locking the cleat in operative position outside of the housing, and means for holding the cleat from displacement when concealed within the housing, a 35 housing cover formed with the cleat, and a supplemental housing cover operative respectively when the cleat is exposed and when it is concealed.

40 6. In a submarine boat, having a well, a cleat pivotally mounted in said well and adapted to be concealed within the well, and a cover for the well adapted to close the well when the cleat is concealed therein, and a lug 45 on the cleat to hold the cleat from displacement when housed.

7. A disappearing cleat for submarine boats, having pivots extending from its base and adapted to be supported in bearings in a 50 housing or well in the boat into which the cleat disappears, said cleat having a plate and means to lock the plate in cleat-supporting position and to close the well when the cleat is extended, and a lug on the cleat 55 adapted to engage an element of the cleat-locking member when the cleat disappears into the housing or well.

In testimony whereof I have hereunto set my hand this 29th day of April, A. D. 1921. 60

HOWARD H. HOFFMAN.
